INVENTOR.
Charles C. Hansen
BY *Robert Adler*
HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

SAND PIPE FOR ROCK DRILLS.

Application filed March 17, 1928. Serial No. 262,471.

This invention relates to fluid actuated rock drills of the type mounted on a barge or other support for drilling submerged material, but more particularly to a sand pipe 5 adapted to extend from the barge to the material intended to be drilled to form a guide for the working implement.

Other objects of the invention are to prevent the admission of silt or broken material 10 into the drill hole, to facilitate the charging of the drill hole and to enable the sand pipe to be readily actuated into and out of the operative position.

Other objects will be in part obvious and in 15 part pointed out hereinafter.

In the drawings forming part of the specification,

Figure 1 is a transverse sectional elevation of a drill barge equipped with sand pipes 20 constructed in accordance with the practice of the invention,

Figure 2 is a front elevation of a portion of a drilling tower showing the sand pipes in the operative position, and

Figure 3 is a similar view showing the position which the sand pipe may occupy during the transportation of the unit from one side to another.

Referring more particularly to the drawings, A designates a barge and B columnar supports or anchors adapted to rest on the rock C for supporting the barge A above the surface of the water D during the drilling operation.

In accordance with the present invention, the barge A is provided with a well E or, as illustrated, a pair of wells E which extend longitudinally of the barge. On opposite sides of the wells E are disposed rails F upon which are slidably mounted drilling towers G. The drilling towers G comprise in this instance vertical guide members H resting on sills J and are supported near their uppermost ends by diagonal bars K connected at one end to the guide members H and at their other ends to the sills J.

Slidably mounted on the guide members H are rock drills L supported by cables O trained over sheaves P at the uppermost ends 50 of the guide members H. The cables O are wound on hoist drums Q mounted on platforms R on the towers G.

In order to prevent the admission of silt and débris such as is usually found on the

bottom of a stream into the drill hole S, the 55 unit is provided with sand pipes T which extend slidably into guide pipes U supported in this instance by the sills J. The guide pipes U are preferably of such length as to extend only a short distance below the barge 60 A and are threaded into heads V having flanges W adapted to slide in guideways X formed by plates Y and Z-bars Z. The plates Y and Z-bars Z are supported by the sills J to which they may be secured in any suitable 65 manner. The sand pipes T may be of any suitable length depending upon the depth of the water D and the bore of said pipes need be only slightly greater than the diameter of the working bits of drill steels b which extend therethrough.

Convenient means are provided for raising and lowering the sand pipes T. To this end sheave blocks e are connected to the lowermost ends of the sand pipes T to receive cables d connected with one end to blocks e attached to the guide pipes U and the opposite end of the cables d may be secured to anchors f on the barge A.

In the operative position, the pipes T and U are of course in coaxial alignment with the rock drills L. When transporting the unit, however, it is desirable that the sand pipes T be elevated somewhat to prevent them from encountering the bottom of the stream. 85 When sand pipes T of considerable length are used, it would, of course, be difficult to elevate the sand pipes while the pipes are in alignment with the rock drills unless the guide members H also were of considerable 90 length. In order to eliminate the necessity of employing guide members H of excessive height, means are provided for moving the pipes T and U out of alignment with the rock drills to a position in which the pipes T may 95 be raised to any desired elevation. The means utilized for this purpose comprise screws g which are in threaded engagement with projections h carried by the heads V. The ends of the screws g are mounted rotat- 100 ably in bearings j and k secured to the sills J and to one end of the screws g are secured crank handles o whereby the screws g may be rotated.

The operation of the device is as follows: 105 After the barge A has been raised above the water D and secured to the anchors B in any suitable and well known manner, the sand

pipes T may be lowered by means of the cables d. Due to the weight of the pipes T said pipes will readily penetrate the silt overlying the rock C and will sink therethrough 5 to the surface of the rock.

After the drill hole has been completed, the rock drills L, together with the drill steels b, will be raised on the guide members K by means of the hoist drums Q. With the drills 10 raised to a point near the top of the towers G, the drill steels b may be removed and withdrawn from the pipes T and U. This operation may readily be accomplished without affecting the position of the sand pipes. After 15 the drill holes S have been charged, the sand pipes T may again be raised by means of the cables d until the lowermost ends of the pipes T are free from the bottom of the stream. The towers G are then moved longitudinally 20 of the barge A to a new position and the pipes T lowered preparatory to a new drilling operation.

Whenever it is desired to move the barge A to another drilling site, the pipes T and U 25 may be moved out of coaxial alignment with the drills by means of the screws g. The sand pipes T may then be raised until the front ends thereof substantially reach the lowermost points of the pipes U. In this position both pipes will clear the bottom of the 30 stream and the barge A may be readily transported from one position to another without

danger of the pipes encountering obstructions in the stream.

I claim:

1. In a drill unit for submarine drilling, the combination of a support and a tower on the support, a rock drill mounted on said tower, a guide pipe, a sand pipe slidable in said guide pipe, and means for actuating the pipes into 40 and out of coaxial alignment with the rock drill.

2. In a drill unit for submarine drilling, the combination of a support and a tower on the support, a rock drill slidable on the tower, 45 a guide pipe, a sand pipe slidable in the guide pipe, means for slidably actuating the sand pipe in the guide pipe, and means for supporting the pipes and for actuating said pipes into and out of coaxial alignment with the 50 rock drill.

3. In a drill unit for submarine drilling, the combination of a support and a tower on the support, a rock drill slidable on the tower, 55 a guide pipe, a sand pipe slidable in the guide pipe, a cable for manually raising and lowering the sand pipe in the guide pipe, and a screw rotatable in the tower and in engagement with the guide pipe for actuating the pipes into and out of coaxial alignment with 60 the rock drill.

In testimony whereof I have signed this specification.

CHARLES C. HANSEN.
